UNITED STATES PATENT OFFICE.

JOSEPH T. AUGER, OF MINNEAPOLIS, MINNESOTA, ASSIGNOR OF THREE-EIGHTHS TO
E. M. FERGUSON, OF ST. PAUL, MINNESOTA, AND THREE-EIGHTHS TO E. DULAC,
OF MINNEAPOLIS, MINNESOTA.

ROTARY PUMP.

1,348,771.

Specification of Letters Patent.

Patented Aug. 3, 1920.

Application filed April 22, 1918. Serial No. 229,988.

To all whom it may concern:

Be it known that I, JOSEPH T. AUGER, a citizen of the United States, residing at Minneapolis, in the county of Hennepin and 5 State of Minnesota, have invented certain new and useful Improvements in Rotary Pumps, of which the following is a specification.

My invention relates to rotary pumps and 10 in particular to pumps of this type for use in connection with fire apparatus. The object is to provide a pump which will have a high degree of efficiency and at the same time will occupy a minimum space.

15 The full objects and advantages of my invention will appear in connection with the detailed description and are particularly pointed out in the claims.

20 Referring to the drawings which illustrate the application of my invention in one form,—

Figure 1 is a vertical section on line 1—1 of Fig. 2. Fig. 2 is a horizontal section on line 2—2 of Fig. 1. Fig. 3 is a vertical transverse section on line 3—3 of Fig. 1. Fig. 4 is a detail showing the packing with which the blades of the rotary pistons are provided. Fig. 5 is a horizontal section of a slight modification.

25 The casing of the pump is made up of three castings, as follows: A base casting 10, an intermediate casting 12, and a top casting 14. The castings 10 and 12 are secured together so as to form water tight joints by 30 bolts 16 located in holes in flanges 18 on the casting 12 and holes in the top of the casting 10. The castings 12 and 14 are secured together so as to form water tight joints by bolts 20 which are located in holes in flanges 35 22 on the casting 12 and holes in the bottom of casting 14. It will be apparent from this construction that the castings may be readily separated and removed from each other in order to afford easy access to the interior 40 parts.

45 The base casting consists of a bottom plate 24, end walls 26, and side walls 28, these walls extending up to a horizontal partition plate 30 having a central opening 32 which allows 50 grit, gravel, etc., to fall into the chamber formed by the parts just mentioned. This chamber is provided with a detachable clo-

sure 34 in order that accumulations of refuse material may be removed whenever desired. This chamber is further provided with a 55 drain pipe 36 controlled by a cock 37. Above the partition, the casting, at its two ends, is provided with inlet openings 38 which form an inlet chamber which is provided with pockets 40 at the two sides. Intermediate casting 12 is so shaped as to have two partially overlapping cylindrical piston chambers 42, as best shown in Fig. 1. The lower sides of this casting are bulged to conform to the shape of the pockets 40, as shown 60 in Fig. 3 in order to form lateral admission ports at 44. As will be seen from Fig. 1 the piston chambers extend downwardly into the intake chamber and the walls of these chambers at their lower line of intersection 65 are provided with a ridge 46 which serves to divide the water entering the two chambers 42. A piston shaft 48 extends axially through each of the chambers 42 and at one end these piston shafts are provided with 70 intermeshing gears 50 while one of said shafts at its opposite end is provided with a gear 52, by means of which power is transmitted to the pump. The shafts extend through stuffing boxes 54 at both sides of the 75 piston chambers, and inside of said chambers, the shafts are provided with a plurality of intermeshing piston blades 56. The edges of these blades are provided with brass packing strips 58 having an insert of hydraulic leather 60, as shown in Fig. 4. The sides of the piston chambers 42 are provided with hydraulic leather strips 62, as shown in Fig. 1, to prevent slipping of water. These strips extend outwardly in a radial direction from the shafts of the pistons. The intermediate casting is provided with bridge members 64, best shown in Fig. 3, and also shown in dotted lines in Fig. 1. These bridge members serve to separate the intake and discharge openings and are each provided with a horizontal groove 66 extending from one shaft to the other and a vertical groove 68 extends from the middle of the horizontal groove downwardly into the 80 pockets 40 to provide for escape of grit, gravel, etc. The intermediate casting at 85 both sides is bulged outwardly to form pockets 70 which constitute discharge ports 90

100

- for the water and allow it to be discharged into the chamber 72 in the upper casting. A plurality of discharge pipes 74 lead from this chamber in order that the water may be readily discharged in all directions. Above the discharge chamber 72 is an air chamber 76 in communication therewith through a port 78 formed in a partition between the discharge chamber and the air chamber.
- 10 Above the air chamber is a priming intake adapted to be closed by a screw threaded plug 80. The pockets 70 at each side of the intermediate casting are separated by a dividing member, preferably formed by an upward extension of the bridge 64 as shown in Fig. 1. From this figure it is apparent that the piston blades 56 of the two rotary pistons or cam-like members sweep past the upward extension or dividing member alternately in opposite directions. This prevents what is known as water-lock, since the water which is being forced by each piston blade is given ample opportunity to escape through the pockets 70 into the discharge chamber 72. The upward extension of the bridge intermediate its length also decreases the liability of slippage of water. Still referring to Fig. 1, it will be seen that the lower surface of the bridge curves downwardly in both directions from its intermediate portion, thereby increasing the vertical dimensions of the bridge and further decreasing liability of slippage.
- 15 The operation and advantages of my rotary pump will be readily understood from the foregoing description. As shown in Fig. 1, the piston chambers extend down into the intake for a considerable distance and hence the downwardly extending piston blades 56 will constantly stand in water. This arrangement entirely avoids the necessity of priming except in very severe weather when the water is drained off through the drain pipe 36. When it is necessary to resort to priming under such conditions the provision of the priming intake makes this extremely easy by merely removing the plug 80. The provision of an air chamber directly over the discharge chamber eliminates the troublesome knocking and hose pulsations which is common in rotary pumps. The entire top of the pump may be readily removed, thus giving complete and easy access to all of the interior parts and providing an easy way for removing inside accumulations of sand and other material. The insert of hydraulic leather in the brass packing strip at each edge of the piston blades prevents the working of metal against metal and greatly adds to the durability and efficiency of the pumps and tends to decrease slippage. The provision of the hydraulic leather strips on the sides of the piston chambers also decreases slippage. On account of the almost com-

plete avoidance of slippage, a considerable reduction in the amount of material used is possible and the seating space required is materially reduced. The provision of the horizontal and vertical grooves in the 70 bridges affords an easy escape for grit, gravel, etc., and greatly decreases the destructive action on the piston blades and the bridge.

In Fig. 5 I have shown a slight modification 75 in regard to the piston blades and hence have designated these blades by the character 56' in this figure. Except for these blades, the construction is the same as that in the other figures. In this modification 80 the rotary pistons, instead of having the piston blades extending all the way across, are separated at the middle and offset so that each blade on one side of the piston is located midway between two blades on the 85 other side of the piston. This results in the water being discharged equally from both sides of the pistons, and counter-acts whatever tendency there might be for the water to surge back and forth. 90

I claim:

1. A rotary pump comprising a base member provided with an inlet chamber, an intermediate chamber containing overlapping piston chambers connected with said inlet 95 chamber, a top member having discharge openings in connection with said piston chambers, a partition in the upper portion of said top member, said partition being provided with a port whereby an air chamber is formed above said partition, the outer wall of said air chamber being provided with a priming opening, and a plug for closing said priming opening. 100

2. A rotary pump comprising a base member provided with an inlet chamber, a partition plate having an opening and constituting the bottom of said chamber, a bottom plate and walls constituting a refuse chamber below said inlet chamber, a detachable closure for said refuse chamber, an intermediate member containing overlapping piston chambers communicating with said inlet chamber, and a top member having discharge openings in communication 110 with said piston chambers. 105

3. A rotary pump comprising a base member provided with an inlet chamber, an intermediate member containing overlapping piston chambers communicating with 115 said inlet chamber, rotary pistons having intermeshing blades in said piston chambers, brass packing strips in the edges of said blades, an insert of hydraulic leather in said strips extending outwardly from 120 the latter, and a top member having discharge openings in communication with said piston chambers. 125

4. A rotary pump comprising a casing containing two overlapping piston cham- 130

bers provided with lateral intake and discharge openings, bridges separating said intake and discharge openings, rotary pistons having intermeshing blades in said piston chambers, each of said bridges being provided with a horizontal groove extending between the shafts of said pistons, and a

vertical groove extending from said horizontal groove to the intake opening, and a top casing having a discharge chamber into 10 which said discharge openings lead.

In testimony whereof I hereunto affix my signature.

JOSEPH T. AUGER.
